UNITED STATES PATENT OFFICE.

PETER SWANSON, OF ELY, MINNESOTA

GRAVITY LOCK.

Application filed May 21, 1926. Serial No. 110,667.

This invention relates to locks or holding means for separable objects, and refers particularly to a gravity lock or catch especially designed for use upon railroad switches; the principal object being to produce an efficient lock or catch of this character operable by gravity, so as to avoid the necessity of springs or the like which are not dependable.

10 Other objects and advantages of the invention will appear in the further description thereof;

In the accompanying drawing, illustrative of one embodiment of the invention

15 Figure 1 is a perspective view of an improved catch in its simplest form as applied to a railroad switch stand handle;

20 Figure 2 is a vertical section through a slightly modified form of lock or catch illustrating the same as being housed in and locking means applied thereto; while

Figure 3 is a broken perspective view showing the locking means, with the cover removed.

25 The necessity of a dependable lock or catch for a switch handle is well known to those versed in the art as well as the advantage of simplicity in construction, to accomplish which I have illustrated my improved 30 catch as mounted upon a metal plate illustrated at 1 which is bolted or riveted in any desired manner to the switch handle 2, the upper end of which is pivotally attached to the switch throwing mechanism above the 35 laterally protruding lug 3 from the switch stand 4, to which the handle is securely attached when the switch is closed. The plate bracket 1 extends somewhat outwardly and upwardly from the handle where it is bent 40 laterally at right angles forming the two spaced lugs 5 and 6 in which is pivotally mounted the horizontal arm 7 of the catch or dog comprising said horizontal portion as well as the other portions thereof indicated 45 at 8, 9, 10, and 11, the same being of a single piece of round iron or steel. The two portions 7 and 9 are substantially parallel though the latter somewhat shorter than the former and being spaced therefrom in an 50 overhanging manner is constantly susceptible to the influence of gravity, and only prevented from normally remaining with the end or finger 11 normally impinging against the plate 1 by a suitable lug or projection 55 12 formed either upon the lower outer corner of the lug 5 or upon the corner of the cov-

ering plate 13, illustrated in Figure 2 of the drawings. The relation between such lug and the portion 8 of the dog is to keep the end of the finger spaced slightly from the outer surface of the plate 1 so that when the handle 2 is thrust downwardly along said lug 3 on the switch stand, which is provided with a suitable hole 14 for the reception of the finger 11, said finger will slip past the chamfered end of the lug 3 and be forced into the hole 14 by the gravitating effect of the dog. To facilitate this operation I prefer also to chamfer or bevel the extreme end of the finger 11 so that the motion past the end of the lug 3 on the switch stand will be as smooth and graceful as possible.

By such a simple attachment it is evident that the switch handle 2 cannot be fully closed without the catch or lock functioning, and can be only opened by manual manipulation of the locking dog, and to assist in which I have shown a slight extension of the inner end of the bent portion 8 as at 15 forming a convenient thumb hold for raising 20 the dog.

In Figures 2 and 3 I have illustrated means for holding or closing the major portion of the catch, and a locking device therefor, which embodies the forming of a flat side on the portion 7 of the bolt or dog and directly above this portion 7 is a horizontal wall 17 spaced from the wall 18 and parallel therewith, between which two walls the locking pawl or dog 19 is pivotally mounted as at 20, so that the free end of it normally tends to drop in between the portion 7 of the bolt and the wall 18, which naturally takes place at any time the locking bolt is closed to locked position; this pawl also operating wholly by gravity. To raise the pawl 19, as by the common key 21, a key hole 22 is formed in the wall 18, and a suitable key pin 23 is attached to the wall 17 beneath the pawl 19 and by insertion of the key and turning same the lug on the key will engage the under side of the pawl and raise it so that the catch or lug may be opened.

From the foregoing it is evident that I have devised an exceedingly simple lock or catch for not only the purpose intended by one that may be applied to various separable objects.

Having thus described my invention, what I claim and desire to secure by Letters Patent, is:

1. A catch of the character described com-

2
prising a support, a dog having a horizontal portion rotatably mounted within the support and a second portion parallel with the rotatable portion and spaced therefrom, 5 and an inwardly protruding finger depending from the free end of the second horizontal portion for registration with a hole in a cooperative member.

2. The combination with a switch stand 10 having a pivotally mounted operating handle attached thereto and a lug projecting from the stand having a hole therein, of a gravity lock attached to the handle for co-

operative engagement with the hole in the lug.

3. The combination with a switch stand having a pivotally mounted operating handle attached thereto and a lug projecting from the stand having a hole therein, of a gravity catch attached to the handle for co-operative engagement with the hole in the lug, and gravity means for automatically locking the catch.

In testimony whereof I hereunto affix my signature.

PETER SWANSON.
